Hiram Thompson

United States Patent Office.

HIRAM THOMPSON, OF WORCESTER, MASSACHUSETTS.

Letters Patent No. 63,766, dated April 9, 1867.

IMPROVED MACHINE FOR SHAPING AND HEADING BARS OF METAL.

The Schedule referred to in these Letters Patent and making part of the same.

TO ALL WHOM IT MAY CONCERN:

Be it known that I, HIRAM THOMPSON, of Worcester, in the county of Worcester, and State of Massachusetts, have invented new and useful improvements in Machinery for Shaping and Heading Bars of Metal; and I do hereby declare that the following is a full, clear, and exact description of the construction and operation of the same, reference being had to the annexed drawings, making a part of this specification, the same letters in each figure having reference to the same part.

Figure 1 is a perspective view.

Figure 2 is a sectional view of a portion of the wheel A at the seat of the joint b, with the covering removed so as to show the adjustable seat.

Figure 3 is an external view of the side of the wheel A and cam F, with the stand D removed so as to show the shape of the cam F, and also a slot in the wheel A, through which one of the lifting straps d is seen, and in which the lifting bar 11 slides.

Figure 4 is a sectional view of the wheel A, with the section E removed so as to show the internal construction of the machine.

C is the frame of the machine. A is a continuous rotary wheel, in which are constructed presses, by means of which the bars of metal are pressed into the form desired.

These drawings represent an arrangement for manufacturing corrugated railroad spikes. One press only is shown here, which is constructed as follows:

b is a knuckle-joint attached to the wheel A at u, a jaw extending from the circumference of the wheel A to and encircling the shaft S, on which it swings, giving it a motion in the direction of the circumference of the wheel A. To this jaw is attached the other end of the joint b at a. f is one part of the die which gives form to the bar of metal n, which is fastened to the reciprocating jaw a by screws or bolts, and reciprocates with it. e is the other part of the forming die, made fast to the wheel A. B is a continuous rotary wheel revolving in a direction opposite to that of the wheel A. The joint b at the end u has an adjustable seat, c, which has a wedge, o, back of it, adjusted by the screws 1 and 2. It is clearly shown in fig. 2 that by loosening the screw 2 and screwing in the screw 1, the wedge o is forced towards 1, thus forcing the seat c towards the joint b, overcoming the wear of the machine in that direction.

To operate the machine, the iron being cut the desired length and heated, the machine is set in motion; when the press gets into the position shown in fig. 1, the operator places the heated iron in the cavity between i e, fig. 1. When the wheel B comes in contact with the joint b, the joint b is forced down into the position shown in fig. 4, which carries f in the direction of the circumference of the wheel A towards the stationary die e; this corrugates and points the bar. When the projecting end of the bar thus held fast in the press comes in contact with the face of the wheel B, it is upset and forced into the cavity of the die f e, which forms the head. When the joint b is pressed down, the lifting bar 11 takes the position shown in figs. 3 and 4. This bar is connected with the joint b by the lifting straps d, so that as the wheel A travels it carries the lifting bar 11 with it along the stationary cams F, which are fastened to the stand D and to the frame C, which cams F carry the lifting bar 11 towards the circumference of the wheel A, so that when the bar 11 reaches x, the joint b is thrown out, bringing back the die f with it, relieving the bar n, when it drops out a complete corrugated railroad spike, or bolt, or whatever form the die is adapted to give it. When the press gets around again into the position shown in fig. 1, it is ready to receive another bat and put it through the same process.

That which I claim as my invention, and which I desire to secure by Letters Patent, is—

1. The arrangement for giving motion to the jaw a and die f of the knuckle-joint b and wheel B, as described.
2. The combination, with the revolving wheel A, jaw a, and die f, of the wedge o and set-screws 1 and 2, said parts being constructed and arranged for operation substantially as and for the purposes set forth.

HIRAM THOMPSON.
